UNITED STATES PATENT OFFICE.

WILLIAM LEWIS EVANS, JR., OF WASHINGTON, INDIANA.

HINGE.

1,412,108.

Specification of Letters Patent. Patented Apr. 11, 1922.

Application filed December 22, 1919. Serial No. 346,455.

To all whom it may concern:

Be it known that I, WILLIAM L. EVANS, Jr., a citizen of the United States, residing at Washington, in the county of Daviess 5 and State of Indiana, have invented a new and useful Hinge, of which the following is a specification.

This invention relates to a hinge of the multiple pivot lever type, designed particularly for use with the doors of water closets, screen partitions, ventilated wardrobes and other structures, for causing the doors to vanish within the stall frames or compartments, when opened. The invention is an 10 improvement on the construction shown, described and claimed in my Patent Number 1,367,954, dated Feb. 8, 1921.

The object of the invention is to provide a hinge for the doors of the structures 20 named, which, when the door vanishes within the compartment or stall is caused to lie along the side of the compartment, thereby enabling the use of a shorter stall or compartment, than if the door were arranged to swing in on ordinary hinges.

A further object of the invention is to provide a hinge for the doors of such structures which is more easily and conveniently operated than the ordinary door hung to 30 swing inwardly, it being possible by the present invention for the operator to stand near the entrance and close the door, and not have to step out of the way, as the door closes by moving around him.

35 A further object is to provide a hinge which will prevent the door from sagging, will work noiselessly and with little effort, and will not permit slamming of the door, and which will cause the door to stay open 40 or closed or partially so.

In the aforesaid patent, I have disclosed a hinge for connecting a movable member, such as a door, to a stationary member, such as a booth or other compartment, said 45 hinge comprising two pairs of arms, each pair being located respectively at the top and bottom of the door, the pair at the top being pivoted to the inside face of the door and to the top of the compartment, and the 50 pair at the bottom to the inside face of the door and the bottom of the compartment. The pivots of the arms on the door and on the compartment are spaced apart, with the space between the pivots on the door 55 greater than the space between the pivots on the compartment, the pivots on the door

being arranged on opposite sides of the vertical center of the door but nearer to the center than to the side edges of said door. The pivots on the compartments are located respectively on the floor and ceiling of the compartment thereof on a line substantially at right angles to the entrance of the compartment, and at different distances from such entrance. 60

In the present construction, I have located both pivots on the door at one side of the vertical center of the door, and I have placed the pivots on the compartment on the jamb, instead of on the floor and ceiling 70 thereby giving a clear space to enter the stall or compartment, with no part of the hinge standing in the way to step on or trip the occupant going to or from the stall. 75

The invention will be best understood from a consideration of the following detailed description taken in connection with the accompanying drawings forming part of this specification, with the understanding, however, that the invention is not confined to any strict conformity with the showing of the drawings, but may be changed and modified so long as such changes and modifications mark no material departure from the salient features of 80 the invention as expressed in the appended claims. 85

In the drawings:—

Figure 1 represents a vertical transverse section of a water closet stall looking toward the front so as to show the manner of hinging the door; 90

Figure 2 is a horizontal section on an enlarged scale indicating by dotted lines the progressive movement of the door in shifting from its closed position to its open position; 95

Figure 3 is an elevation looking toward the door, which is shown in its closed position, and illustrating the mounting of the 100 hinge plates or socket members on the jamb and door respectively, and the hinge arms connecting the same;

Figure 4 is a detail perspective view of one of the socket members or hinge plates 105 of the jamb;

Figure 5 is a detail perspective view of one of the socket members or hinge plates of the door;

Figure 6 is a detail perspective view of 110 one of the hinge arms.

Like reference characters indicate cor-

responding parts on the several figures of the drawing.

1, 1, designate the side walls or members of a water closet stall or other compartment having the usual door 2. It is customary in hanging water closet doors to set them up from the floor and down from the top of the opening, and use a shorter door than the height of the opening, and I have followed 10 this plan in illustrating the application of my invention.

The drawing shows a hinge at the top and another hinge at the bottom of the door. As the hinges are duplicates of each other, 15 a description of one will suffice for a full understanding of the other.

Fastened to the part which might be termed the door jamb, designated 3, is a hinge element, plate or socket member 4, 20 preferably of the specific form shown in Fig. 4 of the drawings. It is substantially right angular in plan view, so as to fit around one side and one edge of the jamb, being secured in position by one or more bolts and 25 nuts, indicated by 5, (Fig. 2), the bolts being threaded in transverse holes 6 provided in the hinge plate or socket member 4. At the opposite ends of the hinge plate or member, there are formed substantially cylindrical enlargements or bosses, in which are provided vertical holes or sockets 7, which extend part way through the bosses, as indicated by the dotted lines, Figure 3. When 30 these hinge plates are applied to the door jamb in the manner shown in Figures 1, 2 and 3, the cylindrical bosses are located respectively inside and outside the entrance to the stall or compartment, the inner socket being arranged at an angle to the outer socket. 35 These hinge plates or socket members are shown as formed in one piece, but, obviously, they could be made in two pieces, if desired, without affecting the operation.

Mounted on the inside face of the door at 45 the top and bottom are the socket members or door plates 8, shown in detail in Figure 5. They are shown as made each of one piece, but may be constructed of separate pieces, if desired. Each socket member or door plate 50 is secured to the door by screws or bolts, and has a pair of cylindrical bosses projecting therefrom. These bosses are formed with vertical sockets 9, which extend partway the length thereof, as indicated in dotted lines 55 in Figure 3.

10, 10 designate the individual members of a pair of hinge arms, one part at the top and one at the bottom. As shown in Figure 6 of the drawings, these arms have down- 60 turned terminals 11 and upturned terminals 12. These should be constructed exactly vertical, so as to fit loosely and turn in the sockets 7 of the jamb plates 4 and the sockets 9 of the door plates 8. These arms 65 are of the same length, though it is not ab-

solutely necessary that they should be so constructed. A slight variation would not materially affect the operation of the hinge, but for commercial reasons it is desirable that they should be made of the same length. 70

The construction of the hinge arms 10 does not differ materially from the corresponding elements of the aforesaid patent, but the manner of pivotally connecting said arms to the movable member, (the door), and the 75 stationary member, (the door jamb), is materially different from that disclosed in said patent. In the present application, the socket members 8 are disposed at one side of the vertical axis of the door, instead of on 80 opposite sides of said axis, as in my patent. Moreover, the space between the sockets or pivots on the door, is considerably less than the space between the sockets or pivots on the door jamb. On the other hand, the pivots 85 on the stationary member are not located on the floor and the ceiling as in my patent, but they are fastened to the door jamb, respectively above the floor and below the ceiling. 90

In this way, I have removed all the plates and arms from the floor, giving a clear space to enter the stall and leaving no part of the hinge in the way to step on or trip the occupant going to and from the stall. 95

Also, by fastening the hinge to the jamb the door can be set at any height from the floor or down any distance from the top of the opening. In opening the door, the operator does not have to step out of the way of 100 the door in order to pull it open, for when the door is pulled toward the operator, it moves from him at the same time.

The operation is very clearly illustrated in Figure 2 of the drawings, wherein the progressive movement of the door from the closed to the open position is shown in dotted lines. It will be observed that when the door is closed, as shown in full lines, the inner arm is substantially parallel with 105 the door, the outer arm crossing the top of the door, the pivot of the outer arm on the jamb being outside the door. In the dotted line position, marked *a*, the door has assumed an inclined position, the two arms 110 moving together, though the inner arm has moved somewhat faster than the outer arm. Continuing the opening movement of the door to the dotted line position *b*, the outer arm moves faster than the inner arm, traveling a greater distance in order to assume 115 the position shown by the dotted line *b*. It will be noted that these arms at no time assume a parallel position, standing always at more or less of an angle to each other, 120 as Figure 2 shows. 125

When the door is in its open position, the greater portion of the door vanishes within the stall, only the end of the door projecting beyond the stall entrance. In actual opera- 130

tion the door moves inwardly twice the length of the arms. Hence the extent to which the door vanishes within the stall can be regulated by increasing or decreasing the 5 length of the arms.

The door is more easily operated than an ordinary door which is hung to swing inwardly, for the operator can stand close to the opening and close the door, and not have 10 to step out of the way of the door, as the door closes by swinging around him.

It is within the scope of this invention that it may be adapted for many other uses than for water closet doors, for instance, it 15 could be applied to doors for screen partitions, ventilated wardrobes, and wherever it is desired to provide a hinge in structures in order to economize space.

The construction provides an ideal arrangement for water closets, booths and compartments which are necessarily made as small as possible, and which must be provided with doors to close the same.

The objectionable slamming of the door 25 is done away with by this invention, for the door moves slowly, yet noiselessly, and its operation may be effected with the expenditure of little effort.

By the term "compartment" in the claims, 30 I do not wish to be understood as confining myself to a structure bounded by four walls, for the invention could be applied to doors or other movable members employed to close openings in which the opening would 35 not necessarily be an entrance to a definite compartment. For instance, it might be merely a passageway.

In some applications of the invention a pair of hinges is sufficient, but in a majority 40 of instances, two pairs are necessary.

Certain of the claims of this application are generic to the constructions disclosed in my co-pending applications Serial Nos. 346,456; 447,417; 447,418 and 447,419.

45 Having described the invention, I claim—

1. The combination with a stationary member and a movable member, of a hinge for connecting one end of the movable member to the adjacent side of the stationary 50 member comprising a pair of arms both pivotally connected to the same end of the movable member and to the adjacent side of the stationary member, the pivotal connections of said arms with the movable member being located at one side of the longitudinal center thereof, and the pivotal connections with the stationary member being located on opposite sides of the movable member when the latter is closed.

60 2. The combination with movable and stationary members, of a hinge comprising a pair of arms independently pivoted to said members at spaced points, the pivotal connections of said arms with the stationary member being spaced apart a distance

greater than the pivotal connections with the movable member, and the pivotal connections with the stationary member being located at that side of said member along which the movable member extends when 70 open.

3. The combination with movable and stationary members, of a hinge comprising a pair of arms having downturned and upturned terminals, a socket member secured 75 to the movable member and receiving the upturned terminals, and a socket plate secured to the stationary member and receiving the downturned terminals of said arms, said socket plate when in place on the stationary member having its sockets in angular relation.

4. The combination with movable and stationary members, of a hinge comprising a pair of arms, means for pivotally connecting one of the ends of each of the said arms to the movable member, and other means for pivotally connecting the other of the ends of each of said arms to that side of the stationary member along which the movable member swings when in open position, said arms being arranged out of parallelism with each other at all periods of their movement, whereby the movable member may be caused to swing from an open to a closed position. 90

5. The combination with a compartment having a door member, of a hinge for the door member comprising two pairs of arms, and means for independently pivoting each pair to the door member and the door jamb 100 respectively, the pivotal connections of the arms to the door member being located at one side of the vertical center of the door and at a less distance apart than the space between the pivotal connections of the arms 105 to the door jamb, whereby when the door is closed one of the arms assumes a position substantially parallel with the door, while the other arm is located at an angle to the door.

6. The combination with a compartment having an opening, of a door member for closing said opening, means for pivotally connecting said door member to said compartment, said means comprising two pairs 115 of pivoted arms, one pair at the top and the other pair at the bottom, said arms being pivoted at one of their ends to the face of the door member and at the other of their ends to the door jamb, the pivotal connections of the individual arms of each pair to the door jamb being located in different vertical planes.

7. The combination with a compartment having an opening, of a door member for closing said opening, means for pivotally connecting said door member to said compartment, said means comprising two pairs of pivoted arms, one pair at the top and the other pair at the bottom, means for piv- 125

- otally connecting each of said arms at one of their ends to the door member at spaced points, and other means for pivotally connecting the other ends of each of said arms 5 to the door jamb at spaced points, the pivotal connections of the individual arms of each pair to the door jamb being located respectively outside of and within the compartment.
- 10 8. The combination with a compartment having an opening, of a door member for closing said opening, means for pivotally connecting said door member to said compartment, said means comprising two pairs 15 of pivoted arms, one pair at the bottom and one pair at the top, means provided on the door for pivotally connecting one of the ends of each of said arms thereto at spaced points at one side of the vertical center 20 thereof, and other means for pivotally connecting the other ends of each of said arms to the door jamb, the pivotal connections of the individual arms of each pair to the door jamb being located in different vertical 25 planes and respectively outside of and within the compartment.
9. The combination with a compartment having an opening, of a door member for closing said opening, means for pivotally connecting said door member to said compartment, said means comprising a pair of arms, means for pivotally connecting one of the ends of each of said arms to the door at spaced points thereon, and an angular socket 30 member secured to the door jamb and carrying sockets located in different vertical planes to receive the other ends of each of said arms, whereby the pivotal connections of the arms to the door jamb are disposed 35 at different distances from the opening to the compartment.
10. The combination with a compartment having an opening, of a door member for closing said opening, means for pivotally connecting said member to said compartment, said means comprising a pair of arms, means for pivotally connecting one of the ends of each of said arms to the door member at spaced points, and other means for 45 pivotally connecting the other ends of each of said arms to the door jamb, the latter means comprising an angular plate fitted to the door jamb and having a pair of sockets in which the ends of the arms are received, 50 said sockets being respectively located inside and outside the compartment.
11. The combination with a compartment having an opening, of a door member for closing said opening, means for pivotally connecting said door member to said compartment, said means comprising two pairs 55 of pivoted arms, one pair at the top and the other pair at the bottom, means for pivotally connecting said arms at one of their 60 ends to the door member at spaced points,
- and other means for pivotally connecting the other ends of said arms to the compartment at spaced points, the pivotal connections of the individual arms of each pair to the compartment being located respectively outside of and within the compartment, and on opposite sides of the door when in its closed position.
12. The combination with a stationary member, of a movable member, and means for pivotally connecting said movable member to said stationary member, so as to move said movable member from an open to a closed position, comprising a pair of arms, means for pivotally connecting said arms to 75 said movable member, and other means for pivotally connecting said arms to said stationary member, said last-mentioned means having the pivots spaced apart and located at different distances from the movable member when in its closed position and disposed at that side of said stationary member toward or against which said movable member swings when open.
13. The combination with a compartment, 80 of a door for closing an entrance or opening thereof, and means for pivotally connecting said door to said compartment, comprising a pair of arms, a socket member having a pair of sockets in each of which one of the ends of each of said arms is mounted to turn, said socket member being fixed to said door at one side of the vertical center 85 thereof, and other means for pivotally connecting said arms to said compartment, said last-mentioned means having the pivots spaced apart and located at that side of said entrance or opening toward or against which said door swings when open.
14. The combination with a compartment, 90 of a door for closing an entrance or opening thereof, and means for pivotally connecting said door to said compartment, comprising a pair of arms, means for pivotally connecting said arms to said door, and 95 a socket plate or member having a pair of sockets in which said arms are pivotally mounted, said socket plate or member being located at that side of said entrance or opening 100 toward or against which said door swings when open.
15. The combination with a stationary member, of a movable member, and means for pivotally connecting said movable member to said stationary member, comprising a 105 pair of arms, means for pivotally connecting said arms to said movable member, and an angular jamb plate or socket member having a pair of sockets, one at each end, providing means for pivotally connecting 110 said arms to said stationary member, said jamb plate or socket member having means for fastening the same directly to the stationary member.
16. A hinge comprising a pair of plates, 115

and a pair of arms, the opposite ends of each arm being pivotally connected to each of the said plates, one of said plates being bent transversely at an intermediate point 5 of its length.

17. A hinge comprising a pair of plates and a pair of arms, one of said plates being bent transversely intermediately of its length so as to dispose its ends in angular 10 relation, one of the ends of each arm being pivotally connected to the ends of the bent

plate, the other end of each arm being pivotally connected to the other plate at spaced points thereon.

In testimony, that I claim the foregoing 15 as my own, I have hereto affixed my signature in the presence of two witnesses.
